UNITED STATES PATENT OFFICE.

ABNER R. MARTIN, OF CHESTER, VERMONT.

ADJUSTABLE LAMP HOLDER.

Application filed March 11, 1926. Serial No. 93,825.

The chief object of this invention is to provide a holder adapted to be quickly and conveniently secured to and removed from either of a number of parts of a motor vehicle, or any other support, on which it is desirable to adjustably mount a lamp so that the lamp may be located in various positions relative to a vehicle or other support, and its light may be projected in various directions and maintained where projected.

I attain this object by the improvements hereinafter described and claimed.

Of the accompanying drawings forming a part of this specification,—

Figure 1 is a side view of a lamp holder embodying the invention.

Figure 2 is a section on line 2—2 of Figure 1.

Figure 3 is a section on line 3—3 of Figure 2.

Figure 4 is a section on line 4—4 of Figure 1.

Figure 5 is a fragmentary view similar to a portion of Figure 2 showing a modification, 25 the jaws being engaged with a support.

Figures 6 and 7 are side views on a reduced scale, each showing the holder engaged with a support, and a lamp engaged with the holder.

80 The same reference characters indicate the same parts in all of the figures.

In the drawings, 12 designates a tubular standard, to one end portion of which is fixed an inner jaw 14 projecting laterally from the standard and preferably fixed thereto by an internally threaded socket 15 formed on the inner end of the jaw, and engaged with an external thread on the standard as shown by Figures 2 and 5.

40 16 designates a slide movable in the standard. Fixed to the slide is an outer clamping jaw 17 projecting laterally from the slide and the standard, and adapted to cooperate with the inner jaw 14 in grasping

45 an interposed support, such as a mud guard 18 (Figure 6), or a windshield frame 19 (Figures 5 and 7), the jaws holding the standard substantially perpendicular to the support.

The standard and slide are provided with means for preventing rotation of the slide in the standard and maintaining the outer jaw in position to cooperate with the inner jaw. I prefer to embody said means in a guiding slot 20 (Figures 2 and 55 4) in the outer side of the standard, this

being the side from which the jaws project, and a shank portion 17^a connecting the jaw 17 with the slide and formed to move in the slot 20. If desired, however, said means may be embodied, as shown by Figure 5 60 in a slot 21 formed in the inner side of the standard, and a screw or stud 22 fixed to the slide and formed to run in the slot 21, the stud 22 being fixed to a sleeve 23 formed on the inner end of the jaw 17 and slidable 65 on the external surface of the standard 12.

24 designates a spring acting on the slide 16 to press the outer jaw 17 toward the inner jaw 14, said spring being interposed between one end of the slide and an abutment 25 fixed 70 within the standard 12.

It will be seen that the outer jaw 17 may be manually retracted from the inner jaw 14 sufficiently to enable the jaws to be applied to opposite sides of a support, the jaws being 75 caused by the spring 24 to grasp the support when the inner jaw is released by the operator and the spring is thus permitted to project the inner jaw. To facilitate the manual retraction of the slide and the jaw 17, I 80 provide the slide with a handle 26, which, in the preferred construction shown by Figure 2, extends through a slot 27 formed in the standard opposite the slot 20. Upward pressure of a digit of the operator's hand on the handle 26 causes the retraction of the jaw 17. To enable said pressure to be easily applied, I provide the outer end portion of the standard 12 with a laterally projecting rest 29 for another digit of the operator's 90 hand, the arrangement being such that a finger 30 may bear on the rest, while the thumb 31 of the same hand exerts pressure on the handle 26, the finger, bearing on the rest, preventing the standard from moving 95 endwise with the thumb when the latter is retracting the slide and its jaw. The rest 29 may be formed on a sleeve 29^a pinned to the standard 12.

The end portion of the standard 12 opposite the end from which the jaw 14 projects is provided with an automatically contracted frictional socket forming an element of a ball-and-socket joint. Said socket is formed by a semi-spherical contracted end 100 portion 32 of the standard, and a shoe 33 (Figure 2) movable in the standard, and yieldingly pressed by a spring 34 toward the contracted portion 32, the spring bearing at one end on the shoe and at the other end on 110

the abutment 25. The shoe has a cupped outer face 35 as shown by Figure 2, said face and the end portion 32 forming a substantially spherical normally contracted frictional socket adapted to conform to the ball member hereinafter described. The socket portion 32 is provided with a neck-receiving mouth formed by the portions 41 and 42, shown by Figures 1, 2 and 3. 38 designates a 10 lamp-engaging member which is preferably an arcuate resilient strip or clip 38, adapted to yieldingly embrace a lamp body 39. Said member is provided with a shank including a neck 40 extending through the mouth, and 15 a ball 37 fixed to the neck, and frictionally confined by the socket in any position to which it may be turned therein.

The neck 40 and the mouth portions 41 and 42 are formed to permit a limited universal swinging movement of the member 38, as indicated by full and dotted lines in Figures 1, 2 and 3, said member being maintained in either of the positions shown, and 20 in other positions, by the frictional bearing 25 of the shoe 33 on the ball. The neck 40 and the ball 37 constitute a trunnion fixed to the clip 38. Said trunnion is movable in the mouth 41 and slots 42, the arrangement being such that the trunnion may swing in the 30 slots and mouth from side to side of the standard, so that the clip may be located at either of two diametrically opposite sides of the standard, as shown by dotted lines in Figure 2, and at various intermediate positions, one of which is shown by full lines. The trunnion is adapted to turn on its own 35 axis when the clip is in any position to which it may be swung. The slots 42 permit swinging movements of much greater amplitude than are permitted by the mouth 41.

It will be seen that a lamp 39 engaged with the clip 38, may be pointed universally, there being practically no limit to the directions in which the lamp may be pointed by 45 swinging and axial movements of the trunnion.

The terminal may be formed to engage differently formed lamps, the lamp here shown being an ordinary flash light. It may be 50 a spot light or a so-called "trouble" light, supplied with current from a source on a motor vehicle. The jaws 14 and 17 may have any suitable form whereby they are adapted to grasp different parts of a motor vehicle 55 or other support. The inner jaw 14 is preferably a single arm having a recess 14^b in its inner side, while the jaw 17 is preferably wider than the inner jaw and provided with an opening 44 (Figure 4), the portions of

the jaw forming two sides of said opening 60 being provided with recesses 17^b.

The neck portion 40 of the trunnion is cylindrical and its diameter is less than the width of the opening 41 and slots 42, so that the trunnion is adapted to be rotated on its 65 own axis when it and the clip are in any position to which they are bodily movable. The lamp body or member 39 may therefore be rotatively adjusted, so that its longitudinal axis may extend in any desired direction, 70 when the clip is in either of the described positions. The trunnion is fixed to the mid-length portion of the clip 38 and is relatively short, so that the socket, which is rigidly supported in a predetermined position, is in 75 close proximity to the clip and is adapted to frictionally maintain the clip and the lamp member in any position to which they are movable, there being no liability of accidental displacement of the clip and lamp member, by the weight of the latter.

I claim:

A lamp-holder comprising a tubular standard having means whereby it may be confined in a predetermined position on a 85 support and provided with a contracted outer end having a mouth coaxial with the standard, and diametrically opposite slots opening into the mouth, a spring-pressed shoe within the standard, said shoe and contracted end forming a ball-shaped frictional socket, and a lamp-supporting clip having free end portions between which a lamp member is insertible, and a trunnion projecting from the midlength portion of the clip and composed 90 of a ball adapted to turn in said socket, and a neck connecting the ball with the clip, the trunnion being movable bodily and rotatable in the said mouth and slots, the arrangement being such that the trunnion may 100 swing in the slots and mouth from side to side of the standard, so that the clip may be located at either of two diametrically opposite sides of the standard, and in various intermediate positions, the trunnion being 105 adapted to turn on its own axis to permit rotative adjustment of the clip, and various angular positions of a lamp member held thereby, when the clip is in either of said 110 positions, the clip and its trunnion being arranged to hold a lamp member in close proximity to said frictional socket, so that the socket is adapted to frictionally maintain the clip and the lamp member in any position to which they are movable.

In testimony whereof I have affixed my signature.

ABNER R. MARTIN.
